(57) **CLAIM**

The ornamental design for a flower container, as shown and described.

DESCRIPTION

FIG. 1 is a top right perspective view of the flower container of the present invention;

FIG. 2 is a front view thereof;

FIG. 3 is a rear view thereof;

FIG. 4 is a right side view thereof, the left side view being identical thereto; and,

FIG. 5 is a top view thereof.

The portions of the flower container illustrated in broken lines in FIGS. 1 and 5 are included for the purpose of showing portions that form no part of the claimed design.
